(57) **CLAIM**

The ornamental design for a sliding partition panel as shown and described.

DESCRIPTION

FIG. 1 is a front and right perspective view of a sliding partition panel, showing our new design.

FIG. 2 is a front elevation view thereof. A rear elevation view is identical to the front elevation view.

FIG. 3 is a right side elevation view thereof. A left side elevation view is identical to the right side elevation view.

FIG. 4 is a top plan view thereof.

FIG. 5 is a bottom plan view thereof; and,

FIG. 6 is an enlarged cross section of the portion defined by arrows 6 in FIG. 2, taken along the line 6'-6' in FIG. 2.

The broken lines shown in the drawings illustrate portions of the sliding partition panel that form no part of the claimed design. The relatively slim horizontal lines at the ends of relatively thick vertical lines in FIGS. 1, 2 and 3 represent boundaries that form no part of the claimed design.

1 Claim, 6 Drawing Sheets
